UNITED STATES PATENT OFFICE.

JOHN A. THROP AND JOHN COX, OF THREE RIVERS, MICHIGAN.

IMPROVEMENT IN CULTIVATORS.

Specification forming part of Letters Patent No. 37,532, dated January 27, 1863.

To all whom it may concern:

Be it known that we, JOHN A. THROP and JOHN COX, of Three Rivers, in the county of St. Joseph and State of Michigan, have invented a new and useful Improvement in Cultivators; and we do hereby declare that the following is a full, clear, and exact description of the same, reference being had to the accompanying drawings, forming part of this specification, in which—

Figure 1 is top view of our machine as used for preparing the ground for planting wheat. Fig. 2 is a longitudinal section of the same. Fig. 3 is an inverted plan of the cultivator modified and adapted for cultivating young corn. The machine shown in Fig. 1 can be used for the same purpose by withdrawing the pins *a a*, so as to free the intermediate rear shovel-frame, and also removing the front shovel and leg. Fig. 4 is a modification of the laterally-swinging frame shown in Fig. 1.

Similar letters of reference in the several figures indicate corresponding parts.

A is a frame for supporting the fixed cultivator-legs *B B*. This frame may be rectangular in form, or have its sides stand oblique, as represented. The legs *B B* are hung to the frame on pivot-bolts *C C*, and are stayed firmly by means of brace-rods *D D*, which hook to the front of the legs and are confined in metal ears *E E* by means of wooden pins *F F*.

It is desirable to have the shovels, which are on the bottom of the legs, stand parallel with the tongue *G* of the machine; and to attain this end on a *V*-frame we employed in a former patent of ours wedge-blocks of metal or wood, as shown at *b b*; but the same end may be attained, but not with so great strength in the side timbers of the frame, by cutting bevel-sockets in the frame and setting square or other suitable shaped blocks in the positions occupied by the bevel-blocks *b b*. It is also desirable to have the legs *B* rigid under ordinary circumstances; but in the event of the shovels striking a stump or stone it is important that the legs turn on their pivot-bolts, and to secure this we have devised in our former patented cultivator and in this wooden pins and metal ears, so that the stay-rods may break their connection with the ears and move with the legs at such times as may be necessary in

order to obviate the breaking or injury of the shovels. The shovels and their legs are arranged to one side and in rear of one another, starting on opposite sides of a front central leg and shovel, as represented.

The cultivator thus far described is about the same as our patented cultivator, and it may be mounted upon a crank-axle and wheels or be otherwise arranged, as circumstances may require.

To add to the efficiency of cultivators in general, and especially to our patented cultivator, we have contrived the following improvements.

H is a flexible frame with extension-handles *c c*. To the cross-bar of this frame two metal ears, *e e*, are fastened, and on these ears two shovel-legs, *I I*, are hung by means of pivots *f f*. From metal ears *g g* on the front of these legs stay-rods *h h* extend forward. Wooden pins *i i* are used to fasten the rods to these ears. This flexible or jointed frame is pivoted to a cross-bar, *A'*, of the frame *A*, as indicated at *j j*, and the stay-rods *h h* are also pivoted to this cross-bar, as shown at *k k*.

In order to support and guide the rear ends of the jointed frame *H*, bars *A² A²* are placed across the frame *A*, the said bars being placed one underneath the jointed frame and the other on top of the same, as shown in Fig. 2. By this arrangement the frame *H* is kept from vertical movement, but has freedom to move on the pivots *j j* to the right and left when the operator imparts such movements to it. The pivots of the stay-rods allow them to swivel or accommodate themselves to these movements of the frame and the shovel-legs attached to them. The relative positions of the two sets of pivots *j j k k* and the points *m m* of the frame *H* insure a constant unchanging set of the shovel-legs with respect to the line of draft or the tongue of the machine whenever the frame *H* is shifted to the right or left.

In order to keep the flexible frame steady and rigid with the frame *A A* during the use of the cultivator in seaming ground for wheat-planting, stop pins *a a* are inserted through holes provided in the cross-bars *A² A²* and in the side bars of the frame *H*, as shown in Fig. 1. The pins *a a* are removable at pleasure in order that the machine may be used for cultivating young corn.

In cultivating ground for wheat-planting, the cultivator is used just as represented in Figs. 1 and 2, and thus used it equally seams the ground and leaves no large outside seams, such as would be left were not the shovels of the flexible or jointed frame introduced between the hindmost and central front shovel in the manner shown.

Now, in cultivating young or growing corn it is essential to have the shovels of the jointed frame H under control, so that stalks out of the line of the row may be cultivated without being injured. To this end we have pivoted the frame H and the stay-rods of the legs thereof, and by removing the pins *a a* the operator can swing the frame and shovels to the right and left, so as to clear the straggling stalks; and to relieve the operator of the weight of the frame H and its attachments we have provided the supporting and guide bars A' A² for the frame H.

It should be remembered that the front leg and shovel of the cultivator are removed in cultivating growing corn, as shown in Fig. 3.

My cultivator in its use for cultivating growing corn might have its two front legs and shovels, as shown at I' I', Fig. 3, attached by pivots to a slotted slide, H', and in that case the stay-rods h' h' extend forward and fasten to wooden pins of ears g' g', said pins and ears being so constructed with respect to the rods as to allow the rods a chance to accommodate themselves to the lateral movements imparted to the slide H'. To the center of the slide H' a long lever-handle, c', is pivoted, said handle having its fulcrum and support on the under cross-bar, A², as shown. The slide is connected to the under side of the cross-bar A' by means of slots n n and screw-bolts o o, as represented. This arrangement is not so convenient as that shown in Fig. 1, because it does not answer the two purposes of working summer fallow and preparing the ground in seams for sowing wheat, and also for cultivating young corn; but still it contains one part of our invention—viz., the combination of lateral movement, swiveling stay-rods, pivoted legs for shovels, and wooden pins—and therefore we have shown it in this connection.

By examining Fig. 4 of the drawings it will be seen that the legs of the shovels on the frame H are pivoted to the handles *c c* instead of to the cross-piece connecting these handles. With this arrangement the stay-rods are to be attached to the cross-bar A' by the same pivots that fasten the side pieces of the frame H. This plan we do not regard as good as the plan shown in Fig. 1, because it renders a turn or twist of the legs and shovels out of line with the tongue of the machine when the frame H is moved laterally to the right and left. It, however, operates to a certain extent on the same principle as plan Fig. 1.

What we claim as our invention, and desire to secure by Letters Patent, is—

1. The arrangement of the shovel-legs on pivots, in combination with a laterally-adjustable frame or its equivalent, swiveling connecting or stay rods, and yielding connections or wooden pins, substantially in the manner and for the purposes herein described.

2. The flexible or jointed frame H, or its equivalent, in combination with the swiveling stay-rods h, legs I I, cross-bars A' A² A², and the cultivator A, all constructed substantially in the manner and for the purpose described.

3. Adapting the cultivator to the double use of seaming and hillng by the combination of a stiff frame, a jointed pivoted frame, H, and adjustable stops or pins *a a*, substantially as set forth.

4. The jointed frame H, in combination with a rigid frame, when the frame H is pivoted at its front ends and supported by a guide at its rear end, substantially as described.

5. The arrangement of the stay-rods h and the legs I I, in combination with a frame, H, which turns on different fulcrums from those on which the stay-rods turn, substantially as set forth.

JOHN A. THROP.
JOHN COX.
